UNITED STATES PATENT OFFICE.

THOMAS C. DAVIS, OF PUEBLO, COLORADO.

WASHING MACHINE.

Application filed July 21, 1920. Serial No. 397,875.

To all whom it may concern:

Be it known that I, THOMAS C. DAVIS, a citizen of the United States, residing at Pueblo, in the county of Pueblo and State 5 of Colorado, have invented certain new and useful Improvements in Washing Machines, of which the following is a specification.

This invention relates to washing machines and its primary object is to provide 10 a machine of simple and highly efficient construction in which different kinds of clothes can be washed separately and simultaneously.

Another object of the invention is to provide 15 a washing machine of this character in which clothes classified according to their materials or colors, are washed simultaneously in a continuous operation by waters transferred systematically between the different classes, and still other objects reside 20 in the constructions, arrangement and combinations of parts fully described in the course of the following description with reference to the accompanying drawings 25 which illustrate a preferred method of applying the principle of the invention and modifications thereof.

In the drawings in the several views of which like parts are designated by corresponding characters of reference,

Figure 1 represents a plan view of the washing machine in its preferred form;

Figure 2, a sectional side elevation thereof;

Figure 3, a transverse section on the line 3—3, Figure 2;

Figure 4, a fragmentary end elevation of the machine shown in Figure 2 looking in the direction of the arrow X.

Referring in detail to the drawings my improved washing machine comprises an open tub 5 interiorly of semi-cylindrical form and mounted on a suitable supporting structure 6. The tub is divided by vertical 45 partitions 7 into three compartments one of which at an end of the tub has a plug closed outlet 8 for the dirt carrying water after the washing operation is completed.

Two tanks 9 supported upon an elevated 50 structure at the opposite end of the tub are provided with faucets for the supply of hot and cold water to the adjacent compartment thereof.

A plurality of cylindrical drums or barrels 10 partially extending in the compartments of the tub in spaced and concentric

relation to the interior surface thereof are mounted for conjunctive rotation upon a horizontal shaft 12 rotatably supported in boxes which are fastened upon the end walls 60 and the partitions of the tub.

The circumferential wall of each barrel is perforated for the ingress and egress of water contained in the respective compartments of the tub and a portion thereof is 65 loose and hinged at one of its ends as at 14, to permit of opening the barrel for the admission or removal of clothes.

A spring catch 13 at the end of the movable section of the perforated barrel wall 70 opposite to its hinge connection 14 serves to lock it in its closed position.

Each barrel is divided into two compartments by longitudinal partitions 15 alined at opposite sides of its hub and, in effect, 75 constituting one partition, and the different barrels are preferably arranged on the shafts so that their partitions extend angularly with relation to each other, i. e., are staggered, as shown in Figure 3, for the purpose of facilitating their rotary motion by even distribution of the weights of their contents.

Each compartment of the tub, except that at the discharge end which as hereinbefore 85 described has the plug-closed outlet, is connected with the intake opening of a centrifugal pump 16 the outlet of which is connected to an opening in the next adjoining compartment by a conduit 17.

It will be seen that by these means the liquid supplied to the first compartment of the series from the elevated tanks 9, may be transferred successively to the other compartments until it reaches the last compartment from which it is discharged by removing the plug from the outlet.

The operating mechanism of the machine consists of a horizontal driving shaft 18 mounted in bearings on the supporting structure of the tub and carrying a pulley 19 for its connection with a conveniently located source of mechanical energy.

A sleeve 20 slidably mounted on the shaft by means of a feather which prevents its relative rotation, has at its ends beveled gear wheels 21 adapted for separate connection with a corresponding gear 22 at the lower end of a vertical shaft 23 which is mounted for rotation on a bracket 24 at the 110 adjacent end of the tub.

Collars 27 fastened on the driving shaft

by set screws, limit the sliding movement of the connected gear wheels in opposite directions.

A hand lever 25 fulcrumed on the bracket 5 23 has an actuating connection with the sleeve 20 and it carries as usual a pivoted grip 26 in connection with a sliding detent which cooperates with a relatively stationary segment to secure the parts in their adjusted positions.

The shaft has at its upper end a worm 27 which meshes with a correspondingly toothed wheel 28 on a horizontal shaft 29 mounted in bearings at the upper end of 15 the bracket and the end wall of the tub, and a gear wheel 30 on the last-mentioned shaft engages a similar wheel 31 of larger diameter on the shaft 12 of the barrels.

It will be seen that by moving the beveled 20 gear-wheels 21 alternately in engagement with the interposed gear at the end of the worm shaft, the rotary movement of the barrels may be reversed whenever desired for the purpose of subjecting every part of 25 their contents to the cleansing influence of the liquids contained in the respective compartments of the tub.

The operating mechanism of the pumps by which the waters are transferred between 30 the compartments of the tub consist of a beveled gear wheel 32 on the driving shaft which meshes with a corresponding wheel 33 at an end of a shaft 34 mounted in hangers underneath the tub.

35 Beveled gear wheels 35 meshing with similar gears 36 on the rotary elements of the centrifugal pumps are loosely mounted on the shaft 34 so that under normal condition while the barrels are in motion, no action is 40 imparted to the pumps.

A sliding clutch 37 connected for rotation with the shaft by the usual feathers, consists of two connected members 38 adapted for interlocking engagement with the gear 45 wheels 35 which to this end have series of ratchet teeth at the ends of their oppositely extending hubs.

The clutch is pivotally connected to a hand-lever 39 and coiled springs 40 interposed between the clutch members and the respective gears maintain the clutch in its normal inactive position.

In the operation of the washing machine an appropriate quantity of water is supplied to the first compartment of the tub 55 from the supply tanks 9 together with soap or other cleansing preparations and the clothes to be washed are placed in the compartments of the barrel by lifting the hinged portions of the circumferential walls thereof. The clothes are divided so that white goods of fine and delicate fabric are in the first barrel, those of coarser texture in the next adjoining barrel, and the coarsest and

colored pieces in the barrel which rotates 65 in the last compartment of the tub.

The shaft 12 is made to rotate alternately in opposite directions during periods of arbitrary length, by reversing the position of the sliding gears 21 through the medium 70 of the hand lever 25, thereby causing the liquid contained in the compartment of the tub to freely and forcibly circulate through the contents of the barrel into which it enters through the perforations in the circumferential wall thereof.

When the clothes in the first barrel of the series are thoroughly cleansed, the water of the first compartment of the tub is transferred to the second compartment through 80 the medium of the first pump which is operated by moving the clutch 37 into interlocking engagement with the respective beveled gear wheel on the shaft 34.

After the first compartment of the tub 85 has thus been drained, a fresh supply of water is admitted thereto from the supply tanks 9.

The water used in the first operation to cleanse the clothes contained in the first 90 barrel of the series now performs a similar function with respect to the contents of the second barrel while the washed clothes in the first barrel are rinsed by the fresh water entering its perforations as before.

95 After a second period of operation during which the clothes contained in the second barrel are washed, the water of the first and second compartments of the tub are transferred respectively to the next adjoining 100 compartments and the above described operation is repeated until finally the contents of the last barrel have been washed and rinsed, when the remaining water is discharged through the outlet 8.

105 It will thus be seen that by the use of my washing machine, clothes of different grades of fineness or different colors are thoroughly washed at one and the same time without coming in contact with each other 110 and with the same quantity of cleansing and rinsing liquids.

115 It will be apparent that the apparatus is susceptible of variations in the construction and arrangement of its parts within the above stated principle of my invention.

What I claim and desire to secure by Letters Patent is:

120 In a washing machine, the combination of a driving shaft, a plurality of cylindrical drums, each partitioned into two compartments, concentrically mounted on and fast to said driving shaft and disposed with the partitions in staggered relation, and means for rotating said driving shaft.

125 In testimony whereof I have affixed my signature.

THOMAS C. DAVIS.
